UNITED STATES PATENT OFFICE.

OREN F. ROBERTS, OF KANSAS CITY, MISSOURI, ASSIGNOR TO FREDERICK B. CASMIRE,
OF CHANUTE, KANSAS.

WRENCH.

1,401,817.

Specification of Letters Patent. Patented Dec. 27, 1921.

Application filed May 26, 1920. Serial No. 384,283.

To all whom it may concern:

Be it known that I, OREN F. ROBERTS, a citizen of the United States, residing at Kansas City, in the county of Jackson and 5 State of Missouri, have invented a certain new and useful Improvement in Wrenches, of which the following is a specification.

My invention relates to improvements in wrenches.

10 It relates particularly to ratchet wrenches and is of a type employing a screw for turning a nut or bolt, the screw being turned by reciprocation of a handle thereon.

15 The object of my invention is to provide a wrench of the kind described with novel means for effecting turning of the screw, which is simple in construction, relatively cheap to manufacture, durable, not liable to get out of order, which is adapted for use 20 in corners and confined places, such as are found in automobile construction, and which may be used to quickly turn a nut or bolt, which is not accessible to the wrenches usually used for such purposes.

25 The novel features of my invention are hereinafter fully described and claimed.

In the accompanying drawings, which illustrate the preferred embodiment of my invention,

30 Figure 1 is an elevation of my improved wrench.

Fig. 2 is a cross section on the line 2—2 of Fig. 8.

Fig. 3 is a cross section on the line 3—3 of 35 Fig. 8.

Fig. 4 is an enlarged side elevation of the two ratchet members, a portion of the screw, and the pawl shown engaged with one of the ratchet members.

40 Fig. 5 is a view similar to Fig. 4, showing the pawl engaged with the other ratchet members.

Fig. 6 is a side view of the wrench showing the screw locked in its innermost position.

45 Fig. 7 is a vertical sectional view on the line 7—7 of Fig. 6.

Fig. 8 is an enlarged vertical sectional view of a portion of the wrench, showing the 50 pawl lockingly engaging both ratchet members.

Fig. 9 is a cross section on the line 9—9 of Fig. 8.

55 Fig. 10 is a cross section on the line 10—10 of Fig. 8.

Similar reference characters designate similar parts in the different views.

1 designates a handle, preferably T-shaped, provided with a tubular shank 2, in which is longitudinally reciprocative a rotatable 60 screw 3 having two reversely disposed threads 5 and 4, which are respectively engaged with two ratchet members 6 and 7, which are rotatable on the screw 3, and which are provided with oppositely disposed 65 teeth 8 and 9 adapted to be engaged by two teeth 10 and 11 respectively of a pawl 12, Figs. 4 and 5. The pawl 12 is slidably mounted in a longitudinal groove 13, provided in the shank 2, Figs. 7 and 8. 70

When the pawl 12 is in the position shown in Fig. 4, the tooth 10 thereof will engage the teeth 8 and 9 and will hold the ratchet member 6 from turning in one direction. The tooth 11 will be disengaged from the teeth 75 9, thus permitting the ratchet member 9 to rotate with the screw 3. When the pawl is in the position shown in Fig. 5, it will engage the teeth 9 of the ratchet member 7, thus locking said ratchet member. In this 80 position, the tooth 10 of the pawl 12 will be disengaged from the teeth 8, so that the ratchet member 6 is free to turn in either direction.

When the pawl 12 is in the position shown 85 in Fig. 8, it will engage both sets of teeth 8 and 9, and the ratchet members 6 and 7 will both be held from rotation.

For moving the pawl 12, from the intermediate position shown in Fig. 8 to the two 90 positions shown in Figs. 4 and 5, and for yieldingly holding the pawl in the set position, the pawl is held between the ends of a bow-shaped spring 14, the convex side of which, that is the outer side, bears against 95 the inner side of a sleeve 15, which is slipped on and rigidly secured to the shank 2 and which is provided with a longitudinal slot 16, in which is slidably fitted a small slide block 17 which has a milled outer edge and 100 which is rigidly attached to the spring 14 by a pin 18.

As shown in Fig. 2, the ratchet member 6 has a projection 19 which is slidably fitted in the thread 5 of the screw 3. The ratchet 105 member 7 has a similar projection 20 which is slidably fitted in the thread 4, Fig. 3. As shown, the thread 5 is a right hand thread and the thread 4 is a left hand thread.

A longitudinal coil spring 21, Fig. 7, in 110

the shank 2 bears against the upper end of the screw 3 for lifting the handle after it has been forced downwardly to the position shown in Fig. 7.

5 The ratchet members 6 and 7 are held spaced apart by two thin plates 22, Fig. 9, which are respectively mounted in two slots disposed diametrically opposite in the shank 2. The ratchet member 7 is held in place by 10 an externally screw-threaded collar 23, Fig. 8, fitted in the threaded lower end of the shank 2. Mounted in said threaded end is a lock collar 24, which bears against a collar 25 mounted on the screw 3 against the collar 23.

The lower end of the screw 3 is provided with a reduced portion 26 having a longitudinal peripheral groove 27, in which is mounted a flat spring 28, Fig. 8. The portion 26 is adapted to receive the hollow shank of an ordinary wrench socket 29, which is adapted to receive and turn a nut or the head of a bolt. The spring 28 serves merely as a frictional means of holding the socket member 29 from slipping off from the screw. The portion 26 is square in cross section, as is the hole in the shank of the socket member 29, whereby the socket member is made to turn with the screw 3.

30 For holding the screw 3 in its innermost position, shown in Figs. 6 to 8, the screw has a peripheral groove 30, Figs. 7, 8 and 10, adapted to receive therein an inwardly extending pin 31 mounted within a ring 32, which is revoluble on the sleeve 15. The pin 31 extends through a hole 33 in the sleeve 15 and is carried on the free end of a flat spring 34, Fig. 10, which is mounted in a peripheral groove 35, in the sleeve 15, the other end of 35 the spring 34 being rigidly attached to the sleeve 15. The inner side of the ring 32 is provided with a cam groove 36, which permits the pin 31 to be forced out of the groove 30, by the spring 34, when the ring 32 is 40 turned to a position in which the deepest part of the cam groove 36 is opposite the pin 31.

When the ring 32 is turned to the position shown in Fig. 10, the pin 31 will pass out 50 of the groove 36 and will be forced by the inner side of the ring 32 into the groove 30, when the screw 3 has been forced to the innermost position shown in Fig. 8.

A threaded collar 37 fitted in the screw-threaded lower end of the sleeve 15 extends outwardly beyond the inner side of the ring 32, thereby holding the latter on the sleeve 15.

In the operation of my invention, with 60 the parts as shown in Figs. 6 to 8, the screw 3 is held from turning by the engagement of the pawl 12 with both ratchet mem-

bers 6 and 7, so that when the socket member 29 is applied to a nut or bolt head, the wrench may be used like an ordinary 65 T-handle wrench.

When it is desired to have the handle reciprocated to turn the screw 3 in a direction such that a right-hand threaded nut or bolt engaged by the socket member 29 will be 70 screwed inwardly, the block 17 is slid downwardly to the position in which the pawl 12 will engage the ratchet member 7, as shown in Fig. 5, in which position, when the handle is forced downwardly, the ratchet member 7 will cause the screw to turn clockwise or to the right.

To unscrew the nut or bolt, the block 17 is slid to a position in which the pawl 12 will engage the ratchet member 6. Reciprocation of the handle will now cause the ratchet member 6 to turn the screw 3 counter clockwise or to the left, thus unscrewing a right hand nut or bolt.

With my improved wrench, access may be 85 had to bolts or nuts located in corners and in deep confined places and which are not accessible for the use of ordinary wrenches or monkey wrenches.

I do not limit my invention to the structure shown and described, as many modifications, within the scope of the appended claims may be made without departing from the spirit of my invention.

90 What I claim is:—

1. In a wrench, a shank handle, a screw reciprocative therein having two reversely disposed threads, two ratchet members having reversely disposed teeth and rotatable in said handle and respectively fitted to said threads, and a pawl having means for engagement with said handle and movable thereon to two positions in which it will respectively alternately lockingly engage said ratchet members, and movable to an intermediate position in which it will simultaneously lockingly engage both of said ratchet members, substantially as set forth.

2. In a wrench, a shank handle, a screw reciprocative therein having two reversely 110 disposed threads, two ratchet members respectively fitted to said threads and rotatable on said screw, the shank handle having a longitudinal slot, and a pawl slidably fitted in said slot to two positions in which it will alternately lockingly engage said ratchet members, and in an intermediate position simultaneously lockingly engage both of said ratchet members, substantially 115 as set forth.

In testimony whereof I have signed my name to this specification.

OREN F. ROBERTS.
